Primary Examiner — Rhea Shields*(74) Attorney, Agent, or Firm* — Cynthia R. Wright**CLAIM**

The ornamental design for the cylindrical dental filter, as shown and described.

DESCRIPTION

FIG. 1 is an angled top view of the design.

FIG. 2 is an angled bottom view of the design.

FIG. 3 is a left side view.

FIG. 4 is a right side view.

FIG. 5 is a front view; and,

FIG. 6 is a rear view.

In the drawings, the broken lines are for the purpose of illustrating portions of the cylindrical dental filter that forms no part of the claimed design.
